UNITED STATES PATENT OFFICE.

GEORGE E. HERRMANN, OF MORRISTOWN, AND BENJAMIN W. TUCKER, OF SOUTH ORANGE, NEW JERSEY.

BARREL.

1,216,807.

Specification of Letters Patent. Patented Feb. 20, 1917.

Application filed February 17, 1912. Serial No. 678,843.

To all whom it may concern:

Be it known that we, GEORGE E. HERRMANN and BENJAMIN W. TUCKER, citizens of the United States, and residents of Morristown, county of Morris, State of New Jersey, and South Orange, county of Essex, and State of New Jersey, respectively, have invented certain new and useful Improvements in Barrels, of which the following is 10 a full, clear, and exact description.

This invention relates more particularly to metallic barrels comprising a plurality of members having interlocking parts.

One of the principal objects of the invention is to provide a barrel or other container in which each member is provided with flanges along the edges thereof, the flanges along one edge being provided with a groove and the other with a tongue or rib which is 15 adapted to fit into the groove of the flange of the next adjacent stave or member, and each flange being provided with spaced depressed and projecting portions which serve to further interlock the parts and also to 20 strengthen the flanges against spreading at the joints, thus adapting the barrel or container to resist the strains or shocks to which such articles are subjected while in use.

Another object of the invention is to provide a barrel or container which is simple 30 in construction, which may be readily made and assembled, and which is adapted to hold various kinds of material.

A further object of the invention is to provide simple and efficient means whereby the 35 staves or members and the head or heads of the barrel may be locked together and the ends of the barrel or container materially strengthened at its ends.

40 A still further object of the invention is to provide rib and groove connections between the head and the ends of the staves or members.

With these and other objects in view, the 45 invention will be hereinafter more particularly described with reference to the accompanying drawings, which form a part of this specification, and will then be pointed out in the claims at the end of the description.

50 In the drawings, Figure 1 is an elevation, partly broken away and partly in section, of one form of barrel or container embodying our invention.

Fig. 2 is a plan view, partly broken away 55 and partly in section.

Fig. 3 is a detail perspective view of one of the staves or members looking from the outside.

Fig. 4 is an enlarged fragmentary section 60 showing the means for locking the staves or members and heads together.

Fig. 5 is a sectional plan taken on the line V—V of Fig. 3, with an adjacent stave in position.

Fig. 6 is a view similar to Fig. 5 except that the section is taken on the line VI—VI of Fig. 3.

Fig. 7 is a view similar to Figs. 5 and 6 except that the section is taken on the line 70 VII—VII of Fig. 3.

Fig. 8 is a fragmentary view of a slightly different form of joint.

Fig. 9 is a section taken on the line 75 IX—IX of Fig. 8.

Fig. 10 shows a different form of joint from that shown in the other figures; and

Fig. 11 is a sectional plan view taken on the line XI—XI of Fig. 10.

While the invention is shown as applied 80 more particularly to a bilged metallic barrel, it will be understood that the invention is also applicable to barrels or other containers of various constructions.

The barrel body 10 comprises a plurality 85 of staves or members 11. These staves or members are curved and bilged centrally to provide a barrel body which is larger at the center than at the ends in order that the barrel when lying on its side may be readily 90 placed on its end or otherwise handled. Each stave or member 11 is provided at one edge with an inwardly extending flange 12 and along the other edge with an inwardly extending flange 13. The flange 13 is provided with a depressed portion forming a tongue or rib 14, and the flange 12 is provided with a depressed portion 15 forming a groove 16 which is adapted to receive the rib or tongue 14 of the next adjacent stave 100 when the staves or members are assembled to form the barrel or container body. The ribs 14 and the grooved portions 15 as well as the flanges extend the greater part of the length of the staves, and said flanges extend 105 at substantially right angles to the body portion while the tongue and groove portions lie substantially parallel with the body

portion. The flanges 12 and 13 have their outer edges formed with an angular portion 17 in order to prevent the sharp edge of the flange from being exposed, and this edge 5 may be arranged at right angles to the flanges as shown, or in any other preferred manner.

Each flange is provided with spaced projecting portions 18 and 19. These portions 10 are formed by forcing outwardly a part of each of the flanges 12 and 13 and the projecting portions 18 extend in one direction while the projecting portions 19 extend in the opposite direction and alternate with each 15 other so as to provide parts which project from opposite sides of the flanges. These projecting portions 18 and 19 are angular in formation and have their largest portion near the body of the stave and gradually 20 taper toward the outer edges of the flanges 12 and 13, and each projecting portion forms a groove or recess so that the projecting portions of one stave may enter the groove or recessed portions of the projections of 25 the stave next adjacent thereto when the staves are brought together. These projecting portions by interlocking as they do, prevent relative lengthwise movement of the staves or members with relation to each 30 other and serve further to strengthen the flanges and to assist in preventing the same from spreading or opening at the joint and serve further to assist in locking the flanges and staves in a direction opposite to the 35 ribs 14 and groove portions 15.

A head 20 may be located at either or both ends of the barrel or container body, and each head has its body portion 21 concaved or forced inwardly to rest against the 40 shoulders formed by the ends of the flanges 12 and 13, the latter serving in addition to said supports as strengthening ribs for the barrel body. Each head has an outwardly 45 extending flange 22 and is adapted to be seated in a croze or groove formed by the offset portion 23 of the staves or members. The flange 22 is provided with a grooved part 24 which is continuous, and said groove of each head is adapted to receive a tongue 50 or rib 25 located at one of the ends of the staves or members 11, the said staves or members when they are put together forming substantially a continuous annular rib around the head. A wire or other element 55 26 is located in the groove formed by the ribs 25 of the staves, and this wire when tightened will serve to rigidly hold the ends of the barrel staves to the head co-operating therewith. The members or staves 11 have 60 substantially straight outer ends 27 which lie against the flanges 22 of the heads 20, and fitting about the ends of the staves and the flange of each head is a compression band or member 28. This band or member 65 28 has two flange portions 29 and 30, the lat-

ter being joined to the flange 28 by a horizontally extending portion 31 and arranged to lie against the inner surface of the flange 22 of the head and have its inner edge resting against the outer surface of the body 21 70 of said head. The flange 30 may be angular for a part of its length and with the flange 28 forms an annular chamber or recess to receive the flange 22 and ends of the barrel staves. The band may be divided 75 and has an offset part 32 terminating in a short skirt portion 33 which extends lengthwise of the staves or members for a short distance. A wire or band 34 is located under the shoulder of the band or member 28 80 so that when its ends are joined by twisting or otherwise, the band or member 28 may be compressed to further hold the staves or members and heads together and in such a way that the band will materially assist in 85 strengthening the ends of the barrel.

The barrel or container body may be bound intermediate the ends thereof and for this purpose various means may be employed. As shown, each stave or member is 90 provided with a transverse groove which when the staves are put together form substantially annular grooves around the barrel or container body. A wire band 34^a is located in one of the grooves, and a second 95 wire or band 34^b is located in the other groove, so that when the two bands are joined by twisting the ends or otherwise, the body will be bound intermediate the ends and thereby materially strengthened. 100

In Figs. 8 and 9, the members or staves 35 are substantially the same as already described, and the flanges instead of having the projecting portions alternately arranged and projecting from opposite sides of the flanges 105 they project from one side only. In this case, the projecting portions 36 of one flange enter grooves formed by the projecting portions of the flange of the next adjacent stave, otherwise the construction is the same as that 110 already described.

Figs. 10 and 11 show inwardly projecting portions instead of laterally projecting portions which do not interlock or extend one into the other. In this case the projecting 115 portions 37 along one stave are opposed to the projecting portions 38 of the flanges of the next stave and are formed by depressing the stave from the outside thereof. These projecting portions serve in this case principally to strengthen the inwardly extending flanges and to prevent the joint from spreading under the usual strains or knocks while the barrel or container is in use.

From the foregoing, it will be seen that a 125 strong, efficient and inexpensive barrel is provided; that a simple and efficient joint is provided by which the staves or members may be interlocked in two directions; that simple means is provided whereby the inter- 130

locking portions may be materially strengthened and the joint prevented from opening or spreading while the barrel or other container is in use; that simple and efficient means is provided whereby a rib and groove connection is formed between the ends of the barrel staves or members and the head or heads; and that simple means is provided whereby the several parts may be locked together and one part made to assist in strengthening the other.

Having thus described our invention, we claim as new and desire to secure by Letters Patent:—

- 15 1. A barrel or other container having its body comprising a plurality of members each having flanges extending inwardly lengthwise thereof and along its edges for the greater part of its length, said flanges having parts thereof forming rib and groove portions to lock the flanges together, and spaced interlocking portions located on the flanges and formed therefrom.
- 20 2. A barrel or other container having its body comprising a plurality of members each having flanges extending inwardly lengthwise thereof and along its edges for the greater part of its length, said flanges having parts thereof forming rib and groove portions to lock the flanges together, and with oppositely extending spaced interlock-

ing portions located on the flanges and formed therefrom.

3. A barrel or other container having its body comprising a plurality of detachable members each having flanges extending inwardly lengthwise thereof and along its edges for the greater part of its length, said flanges being provided with portions formed therefrom to lock the flanges together against relative movement lengthwise thereof, and with interlocking portions also formed therefrom to prevent relative movement transversely of the other locking means.

4. A barrel or other container having its body comprising a plurality of detachable members each having flanges extending inwardly lengthwise thereof and along its edges for the greater part of its length, said flanges being provided with rib and groove portions to lock the flanges together, and angular spaced interlocking flanges located on the flanges.

This specification signed and witnessed this 13th day of February, A. D. 1912.

GEORGE E. HERRMANN.
BENJAMIN W. TUCKER.
